FOLDABLE DISPLAY DEVICE AND EASEL

Ludwig Ebert, New York, N. Y., assignor to
 Einson-Freeman Co., Inc., Long Island
 City, N. Y., a corporation of Delaware

Application January 4, 1947, Serial No. 720,249

8 Claims. (Cl. 248—35)

1

My present invention relates generally to display devices, and has particular reference to a foldable cardboard display consisting essentially of a display panel adapted to be supported in display position by means of a collapsible easel secured to the back.

The conventional easel consists of a blank of sheet material, such as cardboard, folded to define an attachment section and a hinged wing or wings. The wing is adapted to swing between a position lying flatwise against the display panel and an operative propping position extending rearwardly from the panel.

It is frequently desirable that a display device of this general character be so constructed that it may be collapsed into a smaller bundle, for shipping and storage purposes. Where the collapse is to be achieved by folding the device along a line substantially parallel to the base, a peculiar problem is presented by virtue of the thickness of the sheet stock of which the device is composed.

One way of collapsing the device is to provide the easel with a transverse line of fold, so that the top portion of the easel may swing rearwardly to overlie the bottom portion. If the top portion of the easel is adhesively secured to the top portion of the display panel, this requires that the display panel be cut through along the line of fold. In the alternative, the easel may be permitted to fold rearwardly upon itself, while the display panel is folded forwardly, but in such a case, the top portion of the easel cannot be permanently secured to the top portion of the display panel, and a special means must be provided for holding these parts in engagement when the device is set up.

So that the forward face of the display panel may not be marred by a transverse cut, it is desirable that a folding of the display panel be in the forward direction. It is also desirable, to avoid warping, and to simplify the manufacture and use of the structure, that the easel be permanently secured to both the top and bottom portions of the display panel. It is a general object of the present invention to provide a display device in which these two desirable results are capable of simultaneous achievement.

I accomplish this general objective by providing for a forward folding of both the display panel and the easel, and by forming excess material in the easel wing or wings adjacent to the fold line, so as to compensate for the thickness of the flat stock of which the display panel is composed.

2

Other more particular objects of the invention reside in the particular manner in which this mode of operation is accomplished and in the nature and manner of assembly of the constituent parts whereby the resultant display device is inexpensive to manufacture, simple to use, and unusually staunch and effective in its set-up condition.

I achieve these objects and advantages, and such other objects and advantages as may hereinafter appear or be pointed out, in the manner illustratively exemplified in the accompanying drawings, in which:

Figure 1 is a perspective view, from the rear, of a display device of the present improved character, shown in set-up condition;

Figure 2 is an elevational rear view on a slightly enlarged scale;

Figure 3 is a plan view of the device in set-up condition;

Figure 4 is a cross-sectional view taken substantially along the line 4—4 of Figure 2;

Figure 5 is a rear perspective view of structure in partially collapsed condition; and

Figure 6 is a similar view showing the device in completely collapsed condition.

I have chosen to illustrate a display panel of substantially rectangular contour, adapted, when set up, to rest on its lower edge 10. This panel is provided with a fold line 11 extending in a direction substantially parallel to the edge 10, and defining an upper panel portion 12 and a lower panel portion 13. The panel is composed of flat stock, such as cardboard, and the fold line 11 is preferably produced by a cut which extends from the rear surface part-way toward the front surface. This permits the upper portion 12 to be folded forwardly over the lower portion 13, as indicated most clearly in Figure 6, without impairing the smooth continuity of the front display surface of the panel.

Secured to the rear surface of the panel is a collapsible easel which is also formed of flat sheet stock, such as cardboard or the like. The easel is provided with one or two wings, and I have chosen to illustrate a construction in which there are two such wings. These wings are designated by the reference numerals 14 and 15. The wing 14 is in hinged association with the panel along a substantially vertical line 16 which intersects the line of fold 11; and the wing 15 is similarly hinged along a line 17 which intersects the fold line 11.

The easel portion between the hinge lines 16 and 17 defines an attachment section 18 which is permanently (preferably adhesively) secured

to the rear surface of the display panel both above and below the fold line 11.

The wings 14 and 15 are adapted to swing from the spaced propping positions of Figures 1-4 to the inoperative positions shown in Figure 5, wherein each wing lies flatwise against the display panel. This is the position into which the wings are adjusted when the device is to be collapsed, and the final step consists in folding the structure forwardly, as shown in Figure 6. To permit this desirable result to be accomplished, each of the wings is provided with a transverse fold line. Thus, the wing 15 has a fold line 19 while the wing 14 has a fold line 20. Adjacent these fold lines, the wings are formed with excess material to compensate for the thickness of the flat stock of which the panel portions 12 and 13 are composed. This excess material assumes the form of a pleat 21 adjacent to the fold line 19, and a similar pleat 22 adjacent to the fold line 20. When the wings are in the propping positions, these pleats project toward each other and lie substantially in a plane at right angles to the planes of the wings. To facilitate this action, the attachment section 18 may be completely cut through, at 23, at the level of the fold line 11.

For a purpose presently to be described, the wing 15 is provided with a pair of aligned vertical slots 24 arranged adjacent to and on opposite sides of the pleat 21, and the wing 14 is provided with a similar pair of slots 25.

To hold the wings in their propping positions, a means is provided for engaging the pleats 21 and 22. This means consists of a bracing flap 26 carried by the attachment section 18. The flap 26 together with an attaching link 27, is preferably formed as an integral part of the single blank of which the easel may be composed, and this may be accomplished by cutting through the blank along the oddly shaped line 28. This line is a continuous cut extending downwardly from the point 29, around the flap 26, and upwardly to the point 30. Extending between the points 29 and 30 is a fold line 31 parallel to the fold line 11.

Between the connecting link 27 and the flap 26 there is a fold line 32 so that the parts may be adjusted, as shown most clearly in Figure 4, to dispose the bracing flap 26 in a position substantially parallel to and spaced from the display panel.

Extending into the flap 26 from its opposite edges are the notches 33 and 34. This forms tongues 35 on opposite sides of the notch 33, and tongues 36 on opposite sides of the notch 34. The tongues 35 are adapted to fit snugly into the slots 24, and the tongues 36 are adapted to fit snugly into the slots 25.

When the device is manufactured, the display panel is first completed by cutting it to the desired shape, forming the fold line 11, and embellishing its forward display surface in the desired manner. (This latter embellishment may consist in adhesively securing to the front face of the panel a continuous sheet of lithographed paper or the like.) The easel is also cut and scored in a separate operation to produce the configurations and cut-outs hereinbefore described. The easel is then laid flatwise against the rear surface of the panel, as shown in Figure 5, with the pleats 21 and 22 projecting rearwardly in the manner shown. The superposed parts are then permanently connected by means of adhesive which has been previously interposed

between the attachment section 18 and the rear surface of the display panel.

When the device is shipped or stored, it assumes the position shown in Figure 6.

When the device is set up into display position, the first step is to swing the parts into the relationship of Figure 5, then the wings 14 and 15 are swung rearwardly, and the bracing flap 26 is brought outwardly and caused to engage with the wings. This engagement is effected by frictionally forcing the pleat 22 into the notch 34, and similarly engaging the pleat 21 into the notch 33. At the same time, the tongues 35 are caused to project outwardly through the slots 24, and the tongues 36 are caused to project outwardly through the slots 25. This firmly braces the easel wings and affords an unusually staunch and rigid structure.

The collapsing of the device is accomplished by reversing the procedure, as will be understood.

Obviously, if desired, one of the easel wings may be dispensed with since a single wing may be sufficient under certain circumstances to support the display panel in upright position.

Also, if desired, the device may be further rigidified by providing an ordinary easel-lock in association with one or both wings, either above or below the region where the wing pleats are engaged. The type of easel-lock to which I refer consists of a bracing flap formed as an integral part of the easel material, and adapted to swing into a substantially horizontal direction and into locking engagement with the easel wing or wings when the latter is in propping position.

While, in the present drawings, I have illustrated a device in which the fold line 11 is accurately horizontal, it will be understood that this disposition of the fold line is not essential. It may be inclined without altering the essential character or mode of operation of the device. It is for this reason that this fold line has been described and claimed as being "substantially" parallel to the bottom edge of the display panel. An accurate parallelism is not essential.

In general, it will be understood that the details herein described and illustrated may be modified in various respects by those skilled in the art without necessarily departing from the spirit and scope of the invention as expressed in the appended claims.

Having thus described my invention and illustrated its use, what I claim as new and desire to secure by Letters Patent is:

1. In a display device, a panel foldable forwardly along a line substantially parallel to its bottom edge, and a collapsible easel secured to its rear surface and comprising: an attachment section having portions adhesively secured to the panel both above and below said fold line, a wing hinged to said attachment section and adapted to swing either flatwise against said panel or rearwardly into a propping position, said wing extending across said fold line and being provided with a pleat at the level of said fold line to permit forward folding of the easel along with said panel when the wing is flat against the panel, a bracing flap carried by the attachment section of the easel and provided with a notch adapted to engage frictionally with said pleat when the wing is in propping position, and an additional releasable tongue-and-slot engagement between said bracing flap and said wing.

2. In a display device, the combination of elements set forth in claim 1, said bracing flap when operative assuming a position substantially

parallel to and spaced from said panel, and a link hingedly connecting said flap to said attachment section of the easel, said attachment section, said link, said bracing flap, and said wing forming integral parts of a single flat blank of sheet material.

3. In a display device, a panel foldable forwardly along a line substantially parallel to its bottom edge, and a collapsible easel secured to its rear surface and comprising: an attachment section having portions adhesively secured to the panel both above and below said fold line, a pair of wings hinged to opposite edges of said attachment section and adapted to swing either flatwise against said panel or rearwardly into spaced propping positions, each wing extending across said fold line and being provided with a pleat at the level of said fold line to permit forward folding of the easel along with said panel when the wings are flat against the panel, said pleats facing toward each other when the wings are in propping positions, and a bracing flap carried by the attachment section of the easel and adapted to engage said pleats when the wings are in said propping positions.

4. In a display device, a panel foldable forwardly along a line substantially parallel to its bottom edge, and a collapsible easel secured to its rear surface and comprising: an attachment section having portions adhesively secured to the panel both above and below said fold line, a wing hinged to said attachment section and adapted to swing either flatwise against said panel or rearwardly into a propping position, said wing extending across said fold line and being provided with a pleat at the level of said fold line to permit forward folding of the easel along with said panel when the wing is flat against the panel, and a bracing flap carried by the attachment section of the easel and provided with a notch adapted to engage frictionally with said pleat when the wing is in propping position.

5. In a display device, a panel foldable forwardly along a line substantially parallel to its bottom edge, and a collapsible easel secured to its rear surface and comprising: an attachment section having portions adhesively secured to the panel both above and below said fold line, a wing hinged to said attachment section and adapted to swing either flatwise against said panel or rearwardly into a propping position, said wing extending across said fold line and being provided with a pleat at the level of said fold line to permit forward folding of the easel along with said panel when the wing is flat against the panel, and a bracing flap carried by the attachment section of the easel and adapted to engage said pleat when the wing is in propping position.

6. In a display device, a panel foldable forwardly along a line substantially parallel to its

bottom edge, and a collapsible easel secured to its rear surface and comprising: an attachment section having portions adhesively secured to the panel both above and below said fold line, and a wing hinged to said attachment section and adapted to swing either flatwise against said panel or rearwardly into a propping position, said wing extending across said fold line and being provided with a pleat at the level of said fold line to permit forward folding of the easel along with said panel when the wing is flat against the panel.

7. In a display device, a panel composed of flat stock and foldable forwardly along a line substantially parallel to its bottom edge, a propping wing hinged to the rear surface of said panel along a line intersecting said line of fold, said wing being adapted to swing either flatwise against said panel or rearwardly into a propping position, said wing being provided with a medial transverse fold line allowing forward folding of the wing along with the panel when the wing is flat against the panel, and excess material formed in the wing adjacent to said transverse fold line to compensate for the thickness of said flat stock, said excess material assuming the form of a pleat projecting transversely from the plane of the wing when the latter is in propping position.

8. In a display device, a panel composed of flat stock and foldable forwardly along a line substantially parallel to its bottom edge, a propping wing hinged to the rear surface of said panel along a line intersecting said line of fold, said wing being adapted to swing either flatwise against said panel or rearwardly into a propping position, said wing being provided with a medial transverse fold line allowing forward folding of the wing along with the panel when the wing is flat against the panel, excess material formed in the wing adjacent to said transverse fold line to compensate for the thickness of said flat stock, said excess material assuming the form of a pleat projecting transversely from the plane of the wing when the latter is in propping position, and means for clamping said pleat in said projecting position.

LUDWIG EBERT.
